FUEL INJECTION PUMP FOR INTERNAL-COMBUSTION ENGINES

Filed May 6, 1949

FIG.1

UNITED STATES PATENT OFFICE

2,555,930

FUEL INJECTION PUMP FOR INTERNAL-
COMBUSTION ENGINES

Giuseppe Palumbo, Foggia, Italy

Application May 6, 1949, Serial No. 91,716
In Italy May 17, 1948

9 Claims. (Cl. 103—41)

1

This invention relates to improvements in injection pumps for internal combustion engines, of the valve type as distinguished from slide valve pumps.

An object of this invention is to accommodate the valve in the cylinder head and actuate said valve by means of the piston.

A further object of this invention is to cause the valve to constantly bear on a bored disc which is slidably mounted within the piston and is pressed by a spring.

Further objects of this invention will appear from the appended specification in which reference is made to the accompanying drawing in which Fig. 1 is an axial cross section of a construction of my improved injection pump, and Fig. 2 shows a detail.

On the drawing 1 denotes the pump casing, 2 is the cylinder in which moves the piston 3 in the form of a case having its bottom turned downwardly.

A head 4 is mounted at the top of the cylinder and a valve 5 controlling the Diesel oil inlet is slidably guided therein.

The valve 5 seals on its seat 6 formed in the head 4 in which it is suitably guided for displacement and is pressed by a spring 7 which tends to keep the valve open or removed from its seat.

The valve is formed with a tappet-shaped extension 31 abutting the top flat surface of the disc 8 which is mounted for displacement in the internal cylindrical chamber of the piston 3 and is pressed by a spring 10 enclosed in said cylindrical recess and tending to maintain the disc 8 against an abutment in the form of a resilient ring 11.

12 denotes a longitudinal inlet manifold for the oil which flows through the port 13, chamber 14, bores 15, chamber 16 and radial holes 17 in the head 4 reaching underneath the valve 5.

When the piston 3 is in its lowest inoperative position, it abuts the top surface of the cylinder 21 against which the piston is pushed by the spring 7 of the valve on the last portion of its inward stroke when the spring 10 would no longer be effective on account of removal of the tappet 31 from the disc 8, further movement being checked by the ring 11.

In this inoperative position of the piston, the valve 5 is not pressed by the spring 10, and is merely acted upon by the small spring 7. The valve is therefore open, as shown on the drawing.

Consequently, the oil flows through the valve

2

to the recess above the piston 3 and through the bores 19 in the disc 8 to the inner chamber of the piston 3, filling the latter and all other above described passages.

On lifting the piston 3 by any mechanical, hydraulic, electric or pneumatic means, the valve 7 is now promptly loaded by the spring 10 which overcomes the weaker spring 7 and sharply closes the valve. As the piston is moved further upwards, the oil collected underneath the valve is pushed through the holes 20 in the head 4 towards the injectors on the engine.

The pump is of course provided on its pressure line with the ordinary check valve and all other known devices which are neither described nor illustrated for the sake of simplicity.

Use of the pump according to this invention eliminates in the check valve the usual collar adapted to cause the drop in pressure, thereby eliminating the drawbacks deriving therefrom.

In the construction shown by way of example, the piston 3 of the fuel pump is operated by a hydraulic transmission. A cylinder 21 is arranged in the pump casing 1 underneath the cylinder 2 and a piston 22 moves in said cylinder. The piston 22 is of the usual type employed in injection pumps with the difference that the liquid pumped thereby is lubricating oil instead of Diesel oil.

23 denotes the usual suction and reflux holes in the cylinder 21 and 24 denotes the outer cylinder chamber, which communicates with the annular chamber 25 in the casing connected with the reservoir of the lubricating oil.

It will be obvious that by operating the piston 22 as in a conventional injection pump and by the usual adjusting means, a movement of the piston 3 will be transmitted by a hydraulic transmission effected by the lubricating oil, which will supply deliveries equal to those which would have been supplied by the piston 22 if it had pumped fuel oil as in ordinary pumps, while affording the advantage that the said piston 22 is practically of a longer life, the contact with fuel oil being eliminated.

The life of the piston 3 will also be increased over the normal life of the pistons of injection pumps, although it directly acts on the fuel oil, because the valve function is not performed by the piston, which results in well-known objectionable consequences, the said function being performed by the head valve 5.

In order to feed lubricating oil to the lower cylinder and piston, an upper manifold 26 is provided which communicates through the con-

duit 27 formed in the casing 1 with the annular chamber 25.

The cylinder 2 of the fuel oil pump is formed with a lower flange 2' having a flat surface towards the cylinder 21 and a conical peripheral surface. A packing ring of cork, rubber or other material apt to expand under the action of an axial pressure is fitted on the conical surface.

A metal ring 29 bearing on the ring 28 receives pressure from a coiled spring 30 which ensures a tight seal between the fuel oil circulating above the cylinder 21 and lubricating oil circulating underneath the top surface of said cylinder. Moreover, this resilient packing performs the above function without any risk of deformation of the cylinder 2 and ensuing sticking of the piston 3.

The above described device may be suited for instance by the modification shown on the drawing for transforming conventional pumps for operation according to this invention.

In manufacture of new pumps according to this invention, the construction will be suitably varied without departing from the principle described.

What I claim is:

1. In a fuel injection pump for internal combustion engines, the combination with a cylinder, a hollow piston movable in said cylinder and a head for said cylinder, of a fuel inlet valve cooperating with a seat in said head and guided on its movement in an axial bore in said head, a weak spring between the bottom of said bore and said valve for maintaining the latter in its open position, a disc movable in said piston, a spring stronger than the firstmentioned spring between the disc and piston bottom for maintaining the disc against an abutment on the edge of the recess in the piston and an extension fixedly connected with said valve and bearing on said disc.

2. In a fuel injection pump for internal combustion engines, the combination with a cylinder, a hollow piston movable in said cylinder and head for said cylinder, of a fuel inlet valve cooperating with a seat in said head and, on the other side, an extension projecting into said cylinder, a weak spring between the bottom of said recess and the plunger tending to keep said valve in its open position, and a resilient member in said piston on which said extension bears.

3. In a fuel injection pump for internal combustion engines, the combination with a cylinder, a hollow piston movable in said cylinder and head for said cylinder, of a fuel inlet valve cooperating with a seat in said head and having, on one side, a plunger guided in an axial recess in said head and, on the other side, an extension projecting into said cylinder, a weak spring between the bottom of said recess and the plunger tending to keep said valve in its open position, a disc movable in said piston and having holes for the flow of fuel, a spring stronger than the firstmentioned spring between the disc and piston bottom tending to push the said disc outwardly against the extension on said valve.

4. In a fuel injection pump for internal combustion engines, the combination with a pump casing, pump cylinders in holes in said casing and a head for each of said cylinders, of an annular packing between said body and each of said cylinders held in position by said head, a fuel inlet valve cooperating with a seat in said head and

guided on its movement in said head and a resilient member in said piston for closing said valve when said piston performs its pressure stroke.

5. In a fuel injection pump for internal combustion engines, the combination with a pump casing, of pump cylinders in holes in said casing, said cylinders having at one end an annular outer bearing flange of conical shape, a packing ring of resilient material bearing on the conical surface of said flange between the cylinder and pump casing, a pressure disc on said packing ring, a coiled spring acting on said disc, a cylinder head adapted to load the spring, a fuel inlet valve cooperating with a seat in said head and guided on its movement in said head and a resilient member in said piston for closing said valve, when said piston performs its pressure stroke.

6. In a fuel injection pump for internal combustion engines, the combination with a cylinder, a hollow piston movable in said cylinder and a head for said cylinder, of a fuel inlet valve cooperating with a seat in said head and guided on its movement in an axial bore in said head, a weak spring between the bottom of said bore and said valve for maintaining the latter in its open position, a disc movable in said piston, a spring stronger than the first-mentioned spring between the disc and piston bottom for maintaining the disc against an abutment on the edge of the recess in the piston and an extension fixedly connected with said valve and bearing on said disc, and means for actuating said piston against the action of said stronger spring.

7. In a fuel injection pump for internal combustion engines, the combination with a cylinder, a hollow piston movable in said cylinder and a head for said cylinder, of a fuel inlet valve cooperating with a seat in said head and guided on its movement in an axial bore in said head, a weak spring between the bottom of said bore and said valve for maintaining the latter in its open position, a disc movable in said piston, a spring stronger than the first-mentioned spring between the disc and piston bottom for maintaining the disc against an abutment on the edge of the recess in the piston and an extension fixedly connected with said valve and bearing on said disc, and hydraulic means for actuating said piston against the action of said spring.

8. Injection pump as claimed in claim 7, in which the hydraulic means consists of a pump of which the cylinder freely communicates with the cylinder of the injection pump.

9. Injection pump as claimed in claim 7, in which the hydraulic means consists of an ordinary fuel injection pump, of which the cylinder freely communicates with the cylinder of the first-mentioned injection pump and in which lubricating oil is used as transmission fluid.
